UNITED STATES PATENT OFFICE.

CHARLES G. CURTIS, OF NEW YORK, N. Y., ASSIGNOR, BY MESNE ASSIGNMENTS, TO GENERAL ELECTRIC COMPANY, A CORPORATION OF NEW YORK.

ELASTIC-FLUID TURBINE.

No. 920,438.

Specification of Letters Patent.

Patented May 4, 1909.

Application filed January 19, 1897. Serial No. 619,741.

To all whom it may concern:

Be it known that I, CHARLES G. CURTIS, a citizen of the United States, residing at New York city, in the county and State of New York, have invented a certain new and useful Improvement in Elastic-Fluid Turbines, of which the following is a specification.

My invention relates to elastic fluid turbines constructed and operated upon the principle of the turbine of my Patents Nos. 566,967, 566,968 and 566,969.

My object is to improve the construction of the turbine in particulars which will hereinafter be described.

In the accompanying drawing, forming a part hereof, Figure 1 is a vertical section of one form of the turbine; Fig. 2 is a similar view of a different form; Fig. 3 is a detailed section taken on lines 3—3 in Fig. 1; Fig. 4 is a detailed section taken on lines 4—4 in Fig. 1; and Fig. 5 is a top view and partial section on line 5—5 in Fig. 1, illustrating particularly the improved construction of the stationary intermediate working passage.

A is the shaft of the turbine carrying the wheel upon which the movable vanes are mounted. Upon the shaft is a hub, B, having flanges C C'. To these flanges are bolted or riveted two wrought metal disks, D D'. To stiffen these disks laterally, a number of radial web plates, E, of wrought metal, are placed between the disks and riveted to them. This construction of wheel is highly advantageous in that it secures both lightness and great strength. Upon the periphery of each disk is secured a T-shaped wrought metal ring, F, between which and an outer encircling wrought metal band, G, are placed the curved vanes or buckets, H, forming the movable vanes of the turbine. The buckets, H, are secured in position by rivets, a, which pass through the buckets and the bands, F, G.

I I' (Fig. 1) are the two parts of the inclosing shell or casing, which for turbines of moderate diameter may be made of cast iron, as illustrated in Fig. 1, the part I of the case covering one head and the circumference of the wheel, while the part I' is a plate covering the other head of the wheel. In the case of wheels of large diameter, and where the turbine is operated with a vacuum exhaust pressure within the shell, there will be produced a large external pressure upon the heads of the shell. For these turbines, I pro-

pose to make the heads, J J' of the shell (Fig. 2) of sheet metal, and dish them inwardly as shown to withstand the external pressure. With either construction of the shell, it will be provided at the center of the heads with supporting hubs, K K', through which the shaft A passes. Leakage preventing devices surround the shaft. These hubs are supported on pedestals, L L', and the shaft bearings may likewise be supported on the same pedestals or on other pedestals from the same base. By these means the shell of the turbine will be supported at the center, and the expansion of the shell due to heat, taking place in all directions from the center, will not disarrange the parts of the turbine or interfere with the centering of the shaft in the packings. This construction, while applicable to turbines of all diameters, is particularly advantageous in a wheel turbine of large diameter, such as my turbine.

Connected to one head is the delivery nozzle, M, provided with an adjustable tongue, N, for varying the volume of the fluid jet, without substantial changes in its velocity. Connected with the other head of the shell is the exhaust opening, O. The intermediate stationary passage for conveying the fluid jet from one set of movable vanes to the other is mounted upon a block, P, which is placed in an opening in the circumference of the shell, and has flanges covering such opening, and bolted to the shell to secure the block in place. This construction enables the intermediate stationary passage to be readily removed from the turbine. The stationary passage is composed preferably of a number of vanes, Q, which are mounted on the bottom of the block P, by being riveted between top and bottom plates R, S, in a manner similar to the method of securing the movable vanes. In order to give the necessary expansion or enlargement from the receiving to the delivery end of the stationary passage without unnecessarily increasing the depth of the second set of movable vanes, the intermediate passage is spread out at its delivering end circumferentially, so as to include a greater number of vanes at its delivery end than at its receiving end. This is illustrated particularly in Fig. 5. To keep the delivery angle of the vanes Q, of the stationary passage the same for all of such vanes, it is necessary that these straight or slightly curved delivery ends should start at

points progressively nearer the second set of vanes, as shown in Fig. 5.

What I claim is:

1. In an elastic fluid turbine, a vane-carrying wheel having in combination a plurality of separate wrought metal disks, and separate annular sets of movable vanes carried by the disks at their peripheries and separated laterally a sufficient distance to permit the location between them of the stationary passage carrying the elastic fluid from one set of vanes to another, substantially as set forth.
2. In an elastic fluid turbine, a vane-carrying wheel having in combination a plurality of separate wrought metal disks, separate annular sets of movable vanes carried by the disks at their peripheries and separated laterally a sufficient distance to permit the location between them of the stationary passage carrying the elastic fluid from one set of vanes to another, and braces connecting the disks laterally, substantially as set forth.
3. In an elastic fluid turbine, a vane-carrying wheel having in combination a plurality of separate wrought metal disks, separate annular sets of movable vanes carried by the disks at their peripheries and separated laterally a sufficient distance to permit the location between them of the stationary passage carrying the elastic fluid from one set of vanes to another, and intermediate radial stiffening webs between such disks, substantially as set forth.
4. In an elastic fluid turbine, the combination with the shell and a compound vane-carrying wheel, of a set of stationary intermediate vanes supported so as to be removable radially through the shell, substantially as set forth.
5. In an elastic fluid turbine, the combination with the shell and a compound vane-carrying wheel, of a stationary intermediate passage for carrying the fluid from one set of vanes to another, supported by a block projecting through an opening in the shell, through which it can be removed, substantially as set forth.
6. In an elastic fluid turbine, a compound vane-carrying wheel comprising a hub, two metal disks secured to said hub, radial metal stiffening webs placed between the disks and secured to them, and a separate ring secured to the periphery of each disk, in combination with independent sets of curved vanes secured to the said rings beyond said stiffening webs, leaving between the two sets of vanes a clear annular space for accommodating the intermediate stationary vanes, substantially as set forth.
7. In an elastic fluid turbine, a compound vane-carrying wheel comprising a hub, two metal disks secured to said hub, radial metal stiffening webs placed between the disks and secured to them, and a separate ring secured

to the periphery of each disk, in combination with independent sets of curved vanes secured to the said rings beyond said stiffening webs, an inclosing shell, and a stationary intermediate block having vanes therein for carrying the fluid from one set of vanes to the other, the said block projecting through an opening in the shell, substantially as set forth.

8. In an elastic turbine, the combination of a shell or casing, a wheel mounted therein, a double row of buckets for the wheel, supports for the buckets which are secured to the sides of the wheel, a single row of intermediate buckets located between the rows of wheel buckets, and means for discharging motive fluid against the buckets, substantially as set forth.

9. In an elastic fluid turbine, the combination with a vane-carrying wheel and its shaft, of a circular inclosing shell provided with hubs at the centers of a head; and a leakage preventing device in said hub through which the wheel shaft passes, a bearing for the shaft outside of said leakage preventing device, and a support for said hub and bearing extending to the base, substantially as set forth.

10. In an elastic fluid turbine, the combination with a vane-carrying wheel and its shaft, of a circular inclosing shell, a hub at the center of a head of the shell, a leakage preventing device in said hub through which the wheel shaft passes, a bearing for the shaft outside of such leakage preventing device, support for said hub and bearing, a nozzle in one of the heads, an exhaust opening in the other head, and a block removably secured in the circumference of the shell and carrying the intermediate stationary vanes, substantially as set forth.

11. In an elastic fluid turbine, the combination with a vane-carrying wheel, of an inclosing shell having inwardly dished wrought metal heads, hubs secured to the centers of said heads and provided with leakage preventing devices through which the wheel shaft passes, and pedestals supporting said hubs, substantially as set forth.

12. In an elastic fluid turbine, the combination with a circular inclosing shell having inwardly dished wrought metal heads provided with central hubs, and pedestals supporting said hubs, of a vane-carrying wheel mounted in said shell on a shaft which passes through leakage preventing devices in said hubs, and shaft bearings outside of the shell supported from the same base as the shell, substantially as set forth.

13. In an elastic fluid turbine, the combination with a circular inclosing shell comprising a wrought metal ring and inwardly dished wrought metal heads provided with central hubs, and pedestals supporting said hubs, of a vane-carrying wheel mounted in

said shell on a shaft which passes through leakage preventing devices in said hubs, and shaft bearings outside of the shell supported from the same base as the shell, substantially as set forth.

14. In an elastic fluid turbine, the combination with a vane-carrying wheel, of an inclosing shell having inwardly dished wrought metal heads and a wrought metal inclosing 10 ring connecting the heads, the delivery nozzle secured to one of said wrought metal heads and projecting therethrough, the exhaust port secured to the other wrought metal head, and a stationary intermediate passage 15 secured to a block projecting through an opening in the wrought metal ring, substantially as set forth.

15. In an elastic fluid turbine, the combination with a vane carrying wheel having 20 two annular sets of vanes, of an intermediate passage connecting the vanes of the two sets and expanded circumferentially toward its discharging end and means for discharging motive fluid against the vanes in a direction 25 parallel to the axis of the wheel, substantially as set forth.

16. In an elastic fluid turbine, the combination with two annular sets of rotating vanes, of an intermediate stationary passage 30 expanded or enlarged in the direction from its receiving to its discharging end both circumferentially and radially, substantially as set forth.

17. In an elastic fluid turbine, the combination with two annular sets of rotating vanes, of an intermediate stationary passage composed of a number of curved vanes, such 35 passage being expanded circumferentially toward its discharging end, and the delivery 40 ends of the different vanes of the passage being maintained at the same angle, substantially as set forth.

18. In an elastic fluid turbine, a shaft and a vane-carrying wheel formed of a plurality 45 of disks and having annular sets of movable vanes carried by the disks at their peripheries and separated laterally a sufficient distance to permit the location between them of the stationary passage carrying the elastic 50 fluid from one set of vanes to another, there being means other than the shaft connecting the disks together, substantially as set forth.

19. In an elastic fluid turbine, a vane-carrying wheel having in combination a 55 plurality of disks, annular sets of movable vanes carried by the disks at their peripheries and separated laterally a sufficient distance to permit the location between them of the stationary passage carrying the elastic 60 fluid from one set of vanes to another, and means intermediate the center and periphery of the disks for connecting them together, substantially as set forth.

20. In an elastic fluid turbine, the combi-

nation of a shell or casing, a shaft therein, 65 a wheel mounted on the shaft, plural means for supporting a double row of buckets, means other than the shaft connecting the bucket supporting means together, a single row of intermediate buckets located between 70 the rows of wheel buckets and means for discharging motive fluid against the buckets, substantially as set forth.

21. In an elastic fluid turbine, the turbine wheel composed of two or more disks 75 clamped together, rings secured to such disks at their peripheries, vanes carried by such rings and bands encircling the vanes and secured thereto, substantially as set forth.

22. In an elastic fluid turbine, the combination with the shell and vane carrying wheel, of a stationary intermediate passage, supported by a block, the said passage being 80 formed of vanes secured to the block, with a 85 plate between the vanes and the block.

23. In an elastic fluid turbine, a wheel, a member mounted on the wheel, devices to attach the member to the wheel, a plurality of vanes, a separate means for fastening each 90 of the vanes to the said member, and a cover which rests on the outer end of the vanes, and which is separable therefrom, the said cover forming one wall of the vane spaces.

24. In an elastic fluid turbine, a vane 95 carrying wheel having separate vanes, a supporting member for the vanes, and a curved strip between the vanes and supporting member, the said strip being formed of thin stock.

25. In an elastic fluid turbine, a vane-carrying wheel having a rim, separate vanes for axial flow, devices for securing the vanes to the rim in a radial position, a cover connecting the outer ends of the vanes and holding the vanes against centrifugal stress, and devices for securing the cover to the 100 vanes.

26. In an elastic fluid turbine, a vane carrying wheel having separate vanes, a supporting member for the vanes, a strip between the vanes and supporting member, and a strip or cover connecting the outside 11 ends of the vanes and secured thereto.

27. In an elastic fluid turbine, a vane-carrying wheel having separate vanes, a supporting member for the vanes, a strip between the vanes and supporting member, and a strip or cover connecting the outside 12 ends of the vanes and secured thereto, the inner and outer ends of the vanes being flat where in engagement with the strips.

This specification signed and witnessed this 8th day of Jan. 1897.

CHARLES G. CURTIS.
